J. H. STEVENS

RAIL OR TRACK CLAMP

Filed April 17, 1922

Inventor
J.H.Stevens.

By *William J. Jacobi*
Attorney

UNITED STATES PATENT OFFICE.

JOHN H. STEVENS, OF SANDUSKY, OHIO.

RAIL OR TRACK CLAMP.

Application filed April 17, 1922. Serial No. 553,317.

To all whom it may concern:

Be it known that JOHN H. STEVENS, a citizen of the United States, residing at Sandusky, in the county of Erie and State 5 of Ohio, has invented certain new and useful Improvements in Rail or Track Clamps, of which the following is a specification.

This invention relates to a jaw clamp adapted to be securely clamped to the track 10 portion of a railroad tie, and has for its primary object to provide a rail clamp to be used in connection with steam shovels mounted on railroad tracks.

A further object of my invention is to 15 provide a jaw clamp for railroad rails, that can be quickly applied to a rail, and when in position, will act as a chock to prevent backward movement of a steam shovel.

A further object is to provide a rail clamp 20 adapted to be used in all yards and railroad terminals to act as a chock to prevent railroad cars running beyond a predetermined point.

A still further object of my invention is 25 to provide a clamp of the above described character, which consists of three parts, so that in case one of the parts should become broken, it will not be necessary to cast aside the old clamp for a new one, as the broken 30 part can be easily replaced and used with the remaining parts.

A still further object of my invention is 35 to provide a rail clamp of the above described character, that is simple in operation, durable, and efficient for all purposes intended, and one that can be manufactured and placed on the market at a relatively low cost.

These and other objects will be further 40 understood as the description of the invention follows.

The embodiment with which this invention is shown is in the form of a clamp which is adapted to clamp the heads of a rail on all sides. This clamp is shown in the form of a pair of jaws loosely connected through a vertical slot in one of them, so that when a strain is exerted on one of the jaws it causes them to move towards each other firmly grasping the web of a rail. While it is my intention to make this clamp in all sizes, it is so constructed that the largest clamp will fit the smallest rail, in which connection a wedge is used which 55 passes through aligned openings provided in

each of the jaws, so that the wedge will not only grip the top of the rail head, but also cause the jaws to approach each other, and more firmly grip the rail web on both sides. The jaws are also provided with openings 60 that align, through which the wedge can be inserted, so that the wedge will ride cross-wise of the rail, instead of parallel with same as I have hereinafter illustrated and described. 65

Referring to the drawings in detail, like numerals will be used to designate like parts throughout the several views, and

Figure 1 is a side elevation showing my improved clamp applied to use on a rail; 70

Figure 2 is a top plan view thereof; and

Figure 3 is a section therethrough as seen on the line 3—3 of Fig. 1.

Referring in detail to the invention shown in the drawing, 1 and 2 represent a pair of jaws which grip the head of a rail 3 and adapted to hold in position a tie or some other member extending across the railroad track, against which the wheels of a car dredge or other car can rest, so that said car 80 will be held in a fixed position. It has not been deemed necessary to show a tie or other member in the drawings. The clamping member 1 is provided with a shoulder or projection 4, which rests in engagement when 85 in use with a web of a rail while the upper portion of the clamp 1 is provided with a second shoulder 5 adapted to engage a wedge 6 when same is used in connection with the clamping jaws. One of the jaws is 90 approximately U-shaped in cross section, the lower end of same designated by the numeral 7 is adapted to engage the web of a rail adjacent the shoulder 4 of the clamp 1, while the upper portion of same is arcuated 95 and rests firmly on the inclined face of the upper portion of the shoulder 5 of the clamp 1. The clamping jaw 2 is provided with a vertical slot 9 to receive an enlarged portion 10 carried by the shoulder 5 centrally thereof. One of the jaws, in this instance, the jaw 1, is provided with an extension 11, through which is fastened by suitable means a handle 12 so that the device as a whole may be readily lifted, and also that a hook 105 or other connection, not shown, may be readily secured in the handle, thus using the same as an anchor for a tie or hoist rope.

From the foregoing description, it can be readily seen that I have provided a device 110

that is not only efficient and durable for the purpose specified but the same can be readily used in connection with a hoist for removing and replacing new rails on the railroads.

5 When desiring to use my device for the purpose intended, the jaw member 1 is placed in position, the jaw member 2 is then placed on the opposite side of the rail, by passing the same over the handle and extension 11 formed on the clamp 1, said handle and extension passing through the vertical groove 9, and should the clamp be larger than the rail, so that same will not hold securely thereon, a wedge is driven between the 10 aligned openings in the clamping jaws parallel with the rail, or through an opening at right angle to the rail, both of which would cause the jaws 4 and 7 to firmly grip the web of the rail, thus securely anchoring 15 the clamp in position.

20

While I have shown and described a preferred embodiment of my invention, I realize that minor details may be resorted to without departing from the spirit and scope 25 of the invention, therefore, I do not wish to limit myself to the exact details shown or

material used, but wish to make such changes as fall within my invention.

What I claim as new for my invention and desire to secure by Letters Patent is:—

30 1. In a device of the above described character, a pair of substantially U-shaped jaws, one of said jaws provided with an extension on its upper end, a second jaw member provided with a vertical opening, 35 said extension on the first mentioned jaw adapted to extend therethrough, and means for causing the jaws to firmly grasp the web of a rail.

2. In a device of the class described, a 40 pair of substantially U-shaped jaws, one of said jaws provided with an extension on its upper end, the other jaw having an elongated slot therein, said extension on the first mentioned jaw extending through said 45 slot forming interfitting clamping jaws, and a wedge associated with said jaws for causing the latter to firmly grip the web of said rail.

In testimony whereof I affix my signature.

JOHN H. STEVENS.
